CLAIM

The ornamental design for a round hook, as shown and described.

DESCRIPTION

FIG. 1 is a front perspective view of a round hook embodying my new design.

FIG. 2 is a front elevational view thereof.

FIG. 3 is a rear elevational view thereof.

FIG. 4 is a side elevational view thereof. The side opposite to that depicted in FIG. 4 is identical in appearance.

FIG. 5 is a top plan view thereof.

FIG. 6 is a bottom plan view thereof.

FIG. 1

FIG. 2

FIG. 3

FIG. 4

FIG. 5

FIG. 6
